UNITED STATES PATENT OFFICE.

EDWIN F. DRIVER, OF CHICAGO, ILLINOIS.

PHONOGRAPH.

Application filed November 30, 1923. Serial No. 677,735.

To all whom it may concern:

Be it known that I, EDWIN F. DRIVER, a citizen of the United States of America, and a resident of Chicago, county of Cook, and 5 State of Illinois, have invented a new and useful Improvement in Phonographs, of which the following is a specification.

This invention relates to phonographs particularly adapted for use in toys and 10 similar devices, such as cigar cutters, clocks, dolls, saving banks, and the like.

The main objects of this invention are to provide a phonograph of this type having improved mechanism for automatically moving 15 the stylus into and out of contact with the record, and at the end of each operation restoring the stylus carrying arm to its initial position; to provide improved means for controlling the starting and stopping 20 of the phonograph motor; and to provide an improved relative arrangement of said mechanism and means.

An illustrative embodiment of this invention is shown in the accompanying drawings, wherein—

Figure 1 is a plan of the phonograph.

Fig. 2 is a side elevation of the same.

Fig. 3 is a view similar to Fig. 1, but with the record and its support removed for 30 the sake of clearness, and the driving shaft being shown in section.

Fig. 4 is a section taken on the line 4—4 of Fig. 2.

Fig. 5 is an enlarged detail of the mounting for the stylus carrying arm.

In the specific embodiment illustrated, the invention is applied to a phonograph involving the use of a pivoted stylus carrying arm, arranged to be movable laterally 40 across a rotatable record holder which is driven by suitable driving means, such as a small clock mechanism employing a spring motor. Improved control mechanism actuated by the driving means is provided for 45 guiding the stylus into proper engagement with the record and at the end of each operation disengaging it therefrom, and restoring the arm to its starting position ready for another operation. The driving 50 means is automatically stopped by an improved form and arrangement of brake, which is actuated by a cam on the driving means when the control mechanism has restored the stylus arm to its starting position. 55 The brake is manually releasable for starting each operation.

Phonographs embodying this invention are adapted for use with various devices which are well known in the art, and as a detailed description thereof is not essential 60 to a clear understanding of the present invention these devices have been omitted from the drawings.

In the form shown, the phonograph comprises a supporting frame 1, on which is rigidly mounted a tone arm 2 having a diaphragm 3 connected to an improved form of stylus carrying arm 4, which is controlled by an improved construction and arrangement of control mechanism 5. The 70 control mechanism 5 is actuated by driving means 6, coacting with a brake element 7, which is manually releasable for starting the phonograph, and which is automatically actuated by the driving means for stopping 75 the device when the stylus arm has been restored to its starting position. Mounted on the support 1 and driven by the driving means 6, is a rotatable holder 8 for supporting a cylindrical sound reproducing record 9.

As illustrated, the supporting frame 1 comprises a pair of plates 10 and 11 arranged in substantially parallel spaced relation and connected together by bolts 12.

The stylus arm 4 is bifurcated at its outer end, as shown at 13, for pivotally supporting a bell crank lever 14, which is connected at one end to the diaphragm 3 by a wire 15. Mounted on the other end of the lever 14, is 90 a jewel tip 16, for engagement with the record surface. Formed on the inner end of the arm 4, is a pair of ears 17, which are pivoted on a pin 18, supported in a yoke 19. The yoke 19 is also provided with a pair 95 of ears 20, pivoted on a pin 21, supported in a bracket 22, which is rigidly secured to the supporting frame 1. The pins 18 and 21 are arranged at substantially right angles to each other, so as to permit the arm 100 4 to swing laterally across the holder 8 and also toward and away from the record. Embracing the pin 18 and bearing between yoke 19 and arm 4, is a helical spring 22.1, which is arranged to normally urge the outer 105 end of the arm 4 toward the holder 8 for shifting the stylus 16 into engagement with the record. Formed on the yoke 19, is a shoulder 23, arranged in position to coact with one part of the control mechanism 5 110 for rocking the arm 4 around the pin 21 to restore the arm 4 to its starting position,

after the stylus 16 has been disengaged from the record 9 by another part of the control mechanism.

The control mechanism 5 includes a member 24 for shifting the arm 4 away from the holder 8 to disengage the stylus from the record, and a restoring element 25 actuated by said control member for restoring the arm 4 to its starting position.

10 The member 24 is in the form of a lever pivotally mounted on the supporting plate 11 by a pin 26, and having a portion thereof extending at substantially right angles to said supporting plate to form a guide 27 extending across the record holder 8 in position to coact with the stylus arm 4, for shifting said stylus arm away from the record at the end of each operation. Formed at the ends of the guide 27, is a 15 pair of shoulders 28 and 29 for limiting the lateral movement of the arm 4, so as to retain the stylus in proper relation to the record. Formed on the member 24, is a cam element 30, projecting through a slot 31 in the supporting plate 11, so as to be located in position to coact with the driving means 6 for actuating the control member 24, which in turn actuates the restoring element 25. Movement of the lever 24 toward the record 20 holder 8 is limited by a pin 32, mounted on the supporting plate 11.

The restoring element 25 is in the form of an arcuate plate having slots 33 for slidably engaging pins 34, mounted on the supporting plate 11, whereby said element is slideable on said support through an arcuate path. One end of the element 25 is provided with a lug 35 arranged in position to abut against the member 24 when the latter 25 is actuated by the driving means. Formed on the other end of the restoring element 25, is a shoulder 36, adapted to coact with the shoulder 23 of the yoke 19 for restoring the stylus arm, when said arcuate element is 40 actuated by the control member 24.

Mounted on the supporting plate 11, is a spring 37, coacting with the arcuate element 25 for normally urging said element and the control lever 24 into position to release the stylus arm 4. The arcuate element 25 and control lever 24 are relatively arranged so that, during operation of the phonograph, when the lever 24 abuts against the pin 32 and the element 25 is urged under the action 45 of the spring 37 to the limit of its movement as permitted by the studs 34, there will be a space between lever 24 and the lug 35 of the arcuate element. This relative arrangement of the control lever and restoring element permits the control lever to move a predetermined distance under the action of the driving means before actuating the restoring element. This causes the stylus to be 50 disengaged from the record before it is restored to starting position, thereby avoiding

any scratching of the record or injury to the stylus.

In the construction shown, the driving means is in the form of a small clock mechanism comprising a spring motor 38 and governor 39 connected to the record holder 8 by a train of gears numbered 40 to 46 inclusive. The record holder 8 is mounted on a sleeve 47, on which the gear 46 is fixed and which is rotatable on a winding spindle 48 connected to the inner end of the spring motor 38. Mounted on one side of the gear 40 is a stud 49, forming a cam adapted to engage the cam surface 30 of the lever 24 for actuating the control mechanism 5. 50 Mounted on the opposite side of the gear 40, is a stud 50, forming a cam adapted for engagement with the brake element 7 for stopping the driving means. The studs 49 and 50 are relatively arranged so that the stud 50 does not engage the brake element 7 until the control mechanism 5 has restored the stylus arm to its starting position.

The speed of the governor 39 is controlled by an adjusting screw 51, adapted to adjust the tension of a friction pad 52, which bears against a disk 53 of the governor. The governor 39 also includes a hub 54, for engagement with the brake element 7.

The brake element 7 is in the form of a bell crank lever pivotally mounted on the inner face of the supporting plate 11 by a stud 55. Formed on one end of the lever 7, is a brake shoe 56, adapted to be shifted into and out of engagement with the hub 54 of the governor for stopping and starting the driving mechanism. The lever 7 is normally urged into position for releasing the brake shoe by means of a spring 57, mounted on the supporting plate 11 and connected to 100 said one end of the brake element. The other end of the brake element 7 normally extends into the path of the cam 50, so as to be actuated thereby for automatically 105 rocking the brake shoe 56 into engagement 110 with the governor against the action of the spring 57.

The brake lever 7 is manually releasable from the cam 50 for starting the phonograph by means of a pin 58, slidably mounted in the supporting frame 1 and having fixed thereon a lug 59, which is arranged so that when the pin 58 is depressed, the lug 59 engages the end of the lever 7 so as to flex it out of the path of the cam 50, thereby 115 permitting the spring 57 to pull the brake shoe 56 away from the governor hub 54. The lug 59 is provided with an aperture 60 which slidably engages one of the bolts 12 120 of the supporting frame for securing the pin against turning.

In operation, when the brake lever 7 has been released by the depression of the pin 58, the driving mechanism 6 starts under the action of the spring motor 38, and as the 125

cam 49 moves away from the cam surface 30, the control lever 24 and the arcuate element 25 are moved under the action of the spring 37 into position for releasing the stylus arm 4, which thereby moves under the action of the spring 22.1 for shifting the stylus into engagement with the record. When the stylus reaches the end of the record groove, the cam 49 moves into engagement with the cam surface 30, thereby rocking the control lever 24 and its guide member 27 away from the record holder so as to disengage the stylus from the record. After the stylus has been disengaged from the record, the control lever 24 actuates the arcuate element 25 for restoring the stylus arm 4 to its starting position, whereupon the cam 50 moves into position to rock the brake lever 7 so as to shift the brake shoe 56 into contact with the governor, thereby stopping the driving means.

Although but one specific embodiment of this invention has been herein shown and described, it will be understood that numerous details of the construction shown may be altered or omitted without departing from the spirit of this invention as defined by the following claims.

I claim:

- 30 1. A phonograph comprising a support, a record holder rotatably mounted on said support, means for driving said holder, a pivoted stylus carrying arm adapted to rock laterally of said holder to permit the stylus to travel across the record in one direction and being movable toward and away from said holder for shifting the stylus into and out of engagement with the record, said arm being normally urged toward said holder, a control arm pivotally mounted on said support and adapted to coat with said stylus carrying arm for retracting the latter, said control arm being actuated by said driving means, and a restoring element slidably mounted on said support and arranged to coat with said stylus carrying arm for shifting it laterally across said holder in the opposite direction, said restoring element being actuated by said control arm.
- 40 2. A phonograph comprising a support, a record holder rotatably mounted on said support, means for driving said holder, a pivoted stylus carrying arm adapted to rock laterally of said holder to permit the stylus to travel across the record in one direction and being movable toward and away from said holder for shifting the stylus into and
- 45 out of engagement with the record, said arm being normally urged toward said holder, a control arm pivotally mounted on said support and having a part forming a guide member arranged to limit the lateral movement of said stylus carrying arm and adapted to retract said arm for disengaging the stylus from the record, an arcuate element slidably mounted on said holder and adapted to shift said stylus carrying arm laterally across said holder in the opposite direction, said arcuate element being adapted to be actuated by said control arm, a spring 70 coacting with said arcuate element for normally urging said element and control arm into position to release said stylus carrying arm, and a cam on said driving means adapted to engage said control arm for actuating 75 said control arm and arcuate element against the action of said spring.
- 50 3. A phonograph comprising a support, a record holder rotatably mounted on said support, means for driving said holder, a pivoted stylus carrying arm adapted to rock laterally of said holder to permit the stylus to travel across the record in one direction and being movable toward and away from said holder for shifting the stylus into and out of engagement with the record, said arm being normally urged toward said holder, a control arm pivotally mounted on said support and having a part forming a guide member arranged to limit the lateral movement of said stylus carrying arm and adapted to retract said arm for disengaging the stylus from the record, an arcuate element having a pin and slot connection with said support and being actuated by said control arm, a shoulder on said arcuate element adapted to engage said stylus carrying arm for shifting it laterally across said holder in the opposite direction, said control arm and element being relatively arranged so that said element is actuated only after said control arm has moved a predetermined distance, a spring coacting with said arcuate element for normally urging said element and control arm into position to release said stylus carrying arm, and a cam on said driving means adapted to engage said control arm for actuating said control arm and arcuate element against the action of said spring.

Signed at Chicago this 27 day of November 1923.

EDWIN F. DRIVER.
